Des. 223,689
Patented May 23, 1972

223,689

WIG BLOCK STAND

Martin V. Forbes, 7614 Garden St.,
Houston, Tex. 77012

Filed July 28, 1970, Ser. No. 24,196

Term of patent 14 years

Int. Cl. D6—06

U.S. Cl. D80—8

FIG. 1 is a perspective view of a wig block stand showing my new design, the broken line representation of a wig block being for purposes of illustration only; and

FIG. 2 is a bottom plan view thereof.

I claim:

The ornamental design for a wig block stand, as shown and described.
